UNITED STATES PATENT OFFICE

JOHN DANIEL, OF MILWAUKEE, WISCONSIN, ASSIGNOR TO KOEHRING COMPANY, OF MILWAUKEE, WISCONSIN, A CORPORATION

POWER SWING MECHANISM FOR PAVER BOOMS

Application filed September 13, 1927. Serial No. 219,342.

In the operation of boom and bucket pavers, distribution of the concrete is effective over a very wide arc through the adjustment of the swing-boom. This adjustment is secured in the majority of instances by manually shifting the boom about its pivot, either through the instrumentality of a hand operated shaft geared to the boom, or by pressure exerted by the laborers against the outer portion of the boom, as the work proceeds. Both of these methods have numerous disadvantages, among which may be mentioned the fact that, owing to the great force required to effect the swing of the heavy boom and bucket, the gear ratio of the operative connection must be, of necessity, relatively small, with a resulting slow and laborious adjustment. Moreover, the operator's attention must be taken from the other operations of the apparatus incident to the charging of the mixer with water and aggregate materials for too long a time, thus further reducing the efficiency or capacity of the apparatus.

The manipulation of the boom in large apparatus, such as now commonly used, is exceedingly difficult especially where the machine may happen to stand upon an incline and is more less canted to one side in which event the movement of the boom about its pivot through a rising plane is frequently impossible or requires a combined effort of a number of workmen.

The present improvements have as their object to provide a power swing for the boom by which is meant an adjustment of the boom through the application of the motive power of the engine employed for operating the mixer, the bucket, the traveling support and other operating instrumentalities of the apparatus.

To this end the invention seeks to provide a simple mechanism for transmitting motion from the prime mover to the boom so that the latter may be adjusted quickly at any time desired for effective distribution of the materials by the bucket traversing the boom.

In carrying out this idea, I have combined the necessary operating mechanism for adjusting the boom with mechanism employed for shifting the discharge chute of the mixer

so that, by a single control lever, the operator may shift the chute to either its mixing or discharging positions, or swing the boom in opposite directions, as the case may require. However, I do not wish to be restricted to such combined control since it will be quite obvious that the adjustment of the chute and boom may be independently accomplished by a proper segregation of the means for operating these members within the skill of a mechanic familiar with the principles of these mechanisms. 55

In the accompanying drawings:

Fig. 1 is a front elevation of my power swing mechanism applied to a conventional form of paver apparatus, illustrating only such details of the latter as are necessary for a general understanding of these means; 65

Fig. 2 is a side elevation thereof;

Fig. 3 is a detailed view of the clutch shifting fork and its supporting bracket; 70

Fig. 4 is a detailed view of the control lever and its guide block;

Fig. 5 is a sectional view taken about on the plane indicated by the line 5—5 of Fig. 75 1, showing more clearly the operating connections between the power shaft and the respective boom and chute adjusting shafts;

Fig. 6 is a fragmentary view of the clutch housing and its lever accommodating slot and 80 showing the various positions of the control lever for effecting the several boom and chute adjustments; and

Fig. 7 is a horizontal sectional view on the line 7—7 of Fig. 1. 85

Referring to the drawings, and specifically describing the mechanisms, 10 designates the framework of a paver machine on the end of which is pivotally mounted the swing-boom 11 and the swing-chute 12 secured to 90 its adjusting shaft 13 disposed transversely of the frame and having at one end the operating handle 13'.

At one side and extending longitudinally of the frame is arranged the power shaft 14 journalled in the forward bearing 15 and constantly driven by the engine (not shown). On the end of this shaft are the opposed bevel pinions 16—16, each provided with the clutch element 16' with which the respective cone 100

clutches 17 are adapted to engage. The pinions constantly mesh with a gear 18 fixed on the end of a counter-shaft 19 to which motion in reverse directions is transmitted from the power or drum drive-shaft by the engagement of the clutches 17. For effecting this engagement, a control lever 20 is provided, said lever being formed with the yoke 21 embracing the customary ring carried by the clutch spool. The lower end of the lever is formed with a ball or nub 22 which is received by the grooved guide block 23 secured to the bracket support 24 attached to the bearing 15.

Upon the inner end of the counter-shaft is loosely mounted a cable drum 25 formed with a clutch face 26 with which the cooperating clutch face of the intermediate clutch collar 27 is adapted to engage to transmit the shaft motion to the swing-shaft 13 through the cable 28. Necessarily, the clutch collar 27 is splined to the counter-shaft and is shiftable into and out of operative position by the shifter-fork 29, shown in detail in Fig. 3 to be supported by the bracket 30 fixed to the framework 10. The fork 29 carries an arm 31 apertured to receive the connecting rod 32 connected to the control lever 20, as shown in Fig. 4. The end of the arm is disposed between the springs 33 on the rod 32 to provide a snap-over action, as will be more clearly apparent from the following detailed description.

Upon the shaft 19 at the opposite side of the clutch collar is also loosely mounted the sprocket wheel 34 formed with a clutch face 35 and connected by the chain 36 with the boom-swing shaft 37 having an accommodating chain sprocket 38 splined thereon. It so happens that this shaft 37 is the one customarily employed for manually adjusting the boom about its pivot, advantage being taken of such element, where the apparatus is provided with a manual means of this sort; but, of necessity, where no such shaft is employed, one may be provided as a part of the equipment constituting the power-swing mechanism of this invention. Such shaft is provided with an ordinary worm indicated at 39 meshing with the gear segment 40 carried by the boom support. It is also preferably supplied with a hand adjusting wheel 41 so that either the power or hand adjustment of the boom is obtainable, as necessity may require. It will be apparent, from the foregoing description, that the motion of the chain 19 may be transmitted to the shaft 37 for swinging the boom by simply shifting the control lever 20 in the proper direction to bring the clutch collar 27 into engagement with the sprocket 34. The direction of movement of the boom, as well as the direction of movement of the discharge chute will, of course, depend upon the direction of rotation of shaft 19, as controlled by engagement of respective clutches 17. This compound move-

ment, so to speak, of the lever 20 is permitted by the virtue of the engagement of the ball 22 with the grooved guide 23.

To serve as a guide for the respective movements of the lever, I preferably provide the cover of the clutch housing 42 with a guide slot 43, in the shape of the letter H, as shown clearly in Fig. 6. The position of the lever at a is neutral; at b produces a right boom-swing, speaking with reference to the position of the operator when facing toward the boom from his station on the platform of the machine; at c the left boom-swing; at d positions the discharge chute in mixing position and at e in discharge position. Forward and rearward movements of the lever at one side of the slots, therefore, effect chute operations and corresponding movements at the other side of the slot effect boom adjustments.

Having thus described my invention, what I claim as new and desire to secure by Letters Patent of the United States is:—

1. In a concrete paver in combination, a movable chute for a mixing drum, a swingable boom adjacent said chute, an operating shaft operatively connected to said chute and said boom, and common control means for effecting operation of either said chute or said boom from said shaft. 95

2. In a concrete paver in combination, a movable chute for a mixing drum, a swingable boom adjacent said chute, a power operated shaft, means cooperating with said shaft for producing reverse motions, and means intermediate said last named means and the chute and boom for selectively transmitting such motions to either the chute or the boom. 100

3. In a concrete paver, a frame, a swing-boom connected thereto, a swing-chute for a mixing drum and adjacent said boom, a constantly driven operating shaft, a shaft connected to each said chute and boom, and clutch means for transmitting the motion of the operating shaft to the chute and boom shafts, said clutch means having a common control. 105

4. In a concrete paver, a frame, a swing-boom connected thereto, a swing-chute for a mixing drum and adjacent said boom, a constantly driven operating shaft, a counter-shaft operatively connected to the chute and boom, clutch means intermediate the operating shaft and the counter-shaft for driving the counter-shaft in either direction, and clutch means intermediate the counter-shaft and the chute and boom for connecting either the chute or the boom to the reversible counter-shaft. 120

5. In a concrete paver, a frame, a swing-boom connected thereto, a swing-chute for a mixing drum and adjacent said boom, a constantly driven operating shaft, a counter-shaft operatively connected to the chute and boom, clutch means intermediate the operat- 125

ing shaft and the counter-shaft, and control means common to both clutch means.

6. In a concrete paver, a swing-boom connected thereto, a movable chute, an engine operated shaft, a counter-shaft having gear connection with the engine shaft, clutch means on the engine shaft for transmitting reverse motions to the counter-shaft, a shaft operatively connected to the boom, means for transmitting motion from the counter-shaft to the boom operating shaft, a chute operating shaft, means on said counter-shaft for transmitting motion to the chute operating shaft, and a control lever connected to the last named means and to the clutch means on the engine shaft.

7. In a concrete paver, a frame, a swing-boom connected to said frame, a swing-chute mounted on said frame adjacent the boom, an operating shaft, means for swinging the boom or chute from the operating shaft, and a control lever shiftable laterally to transmit motion of the operating shaft to either the chute or the boom and forwardly and rearwardly to effect reverse swing movements of the chute or boom.

8. In a concrete paver, a frame, a swing-boom connected to said frame, a swing-chute mounted on said frame adjacent the boom, a shaft for operating said boom, a second shaft for operating said chute, manual means on each of said shafts for manually operating the respective boom and chute, and power operating means operatively connected to the boom and chute shafts for power operation of said boom and chute.

9. In a machine for distribution of concrete, a discharge chute by which mixed materials may be discharged from a mixing machine, combined with a distributing device for receiving said materials and distributing them to the subgrade, including a boom, and a common control device for causing operation of the chute and for moving the boom to control the distribution action thereof.

10. In combination, a discharge chute for concrete distributing machines adapted to control the discharge of a concrete mixer by which aggregates are commingled, a distributing device cooperative to receive mixed aggregates discharged by the chute and including a boom for facilitating such distribution, power mechanism for the operation of the chute and the said boom, and a control device common to the said parts for their proper operation.

In testimony whereof I affix my signature.
JOHN DANIEL.
